UNITED STATES PATENT OFFICE

108,411

DESIGN FOR A DRESS

Samuel Zahn, New York, N. Y.

Application January 8, 1938, Serial No. 74,146

Term of patent 3½ years

To all whom it may concern:

Be it known that I, Samuel Zahn, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The design is characterized by the particular arrangement of the contrastingly edged ribbon on the skirt, bodice, neck and sleeve portions, as shown.

I claim:

The ornamental design for a dress, substantially as shown and described.

SAMUEL ZAHN.
